RAILWAY RAIL ANCHOR

Filed April 3, 1930

Inventor:
Harry G. Norwood,

By Jas. L. Skidmore

Atty.

UNITED STATES PATENT OFFICE

HARRY G. NORWOOD, OF WASHINGTON, DISTRICT OF COLUMBIA, ASSIGNOR TO THEODORE F. VON DORN, OF NEW YORK, N. Y.

RAILWAY-RAIL ANCHOR

Application filed April 3, 1930. Serial No. 441,285.

This invention relates to an improved and novel one-piece railway rail anchor designed for the purpose of being securely attached to the base portion of the track rails, and adapted to engage with stationary parts of the railway road bed and to prevent longitudinal displacement or creeping of the track rails which has a tendency to occur during the travel of the heavy rolling stock thereover.

10 The prime object of the invention is to provide a simple, economical, durable, practical and efficient one-piece rail anchor, or anti-creeper, possessing a maximum of strength, which when properly applied will effectively resist to a minimum the creeping tendency of the railway track rail.

Another object of the invention is to provide a novel and improved type of rail anchor formed from a single piece of high grade 20 spring steel, preferably heat treated steel, which when properly applied, will under all conditions, serve to rigidly secure the rail and prevent its creeping action toward an adjacent cross-tie.

25 A further object of the invention is to so construct my improved and novel rail anchor that the greater the force of the pressure of the anchor against the cross-tie caused by the travel of the rolling stock over the track rail, 30 the more intense will be the gripping action of the anchor in contact with the rail base.

The foregoing and such other objects as may appear from the ensuing description are attained by the construction, arrangement, 35 combination and location of the several parts hereinafter more fully described, illustrated by the accompanying drawings, and particularly pointed out in the claims appended hereto, it being understood that slight 40 changes in the precise form, proportions and minor details of construction may be resorted to without departing from the spirit or sacrificing any of the advantages of the invention.

45 In the accompanying drawings forming a part of this specification it will be seen that:

Figure 1 is a plan view of a portion of a bar of steel from which my improved rail anchor is formed.

50 Figure 2, is a side elevation of the rail

anchor embodying my invention, showing the anchor applied to the base of a track rail in contact with a cross-tie with the track-rail in cross-section, and the cross-tie broken away.

55 Figure 3 is a plan of the anchor shown in Fig. 2, showing the track rail and cross-tie broken away.

Figure 4 is a plan view of the anchor showing it detached and removed from the track rail, and

60 Figure 5 is an end elevation of the device shown in Fig. 4.

In the drawings as illustrated, it will be seen that Fig. 1 designates a portion of a bar 65 of steel from which my novel anchor is formed, showing a line 2 indicating the line of separation of each anchor, a space 3 showing the maximum amount of waste material 70 that occurs in the formation of each rail anchor, and a slit line 4 in the body portion for the purpose hereinafter described.

75 By reference to Fig. 2 it will be observed that the anchor is shown applied to the base of a standard track rail 5, the said anchor as an entirety, being indicated by the letter A, and is formed from a high grade of spring sheet steel possessing the required thickness and dimensions to furnish a maximum degree of strength, by pressing or stamping the sheet in suitable dies, and at the upper part of the anchor, at one end thereof, is formed an overhanging or overlapping clamping jaw member 6 while at its other end portion is formed a clamping or gripping member 7, 80 said members 6 and 7 being adapted to tightly grip and clamp the base portion of the track rail at each side thereof, respectively.

85 The body portion 8 of the anchor is provided with a slit 4 formed therethrough intermediate its ends, and during the stamping or pressing operation the body portion is forced outwardly in opposite directions between its ends forming the laterally extended members 9 and 10; either member 9 or 10 90 being adapted to engage with the cross-tie 11, when properly attached to the base of the track rail, since it will be readily evident that this type of rail anchor may be easily secured to either side of the base of said track rail.

It will be readily perceived that when the anchor shall have been properly and fixedly secured to the base portion of the track rail with either member 9 or 10 resting in engagement with the cross-tie, the greater the tendency of the rail to creep, the more intense the pressure of the member against the cross-tie thereby forcing the body portion outwardly and at the same time forcing each of its clamping ends inwardly thus intensifying the gripping action of each stamping member at each end in contact with the rail base.

In applying the anchor to the base of the track rail it is simply necessary to place it by hand on one side of the rail base with its jaw member 6 overlapping the upper inclined surface of the rail base with the upper face of the clamping member 7 resting in contact with the lower face of the base of the rail, then by driving the anchor endwise from the left hand end of the device, as shown in the drawings, with a suitable sledge or maul, such as is usually employed for like purposes, until the inner face of the clamping member passes the opposite edge of the rail base when the said clamping member 7 will immediately snap upwardly and tightly grip and clamp the other side of the rail base, all of the parts in contact with said rail base being under intense gripping action with the base of the rail.

This anchor may be readily removed or detached from the rail base by striking the upper face of the clamping member 7 downwardly and then driving it off from the right hand end of the anchor, as will be easily understood.

It will be understood that this particular construction of anchor may be easily applied from either side of the track rail, and that it may be readily detached therefrom and repeatedly used, thereby increasing its longevity.

Having thus described my invention, what I claim and desire to secure by Letters Patent is:

1. A rail anchor formed from a single piece adapted to be fixedly secured to the rail base, comprising a body portion formed with laterally and oppositely disposed formations intermediate its ends, said body portion having a slit therethrough intermediate its ends, and a rail clamping member at each end portion thereof.

2. A rail anchor formed from a single piece of high grade spring steel with an overlapping jaw member at one end and a gripping member at its other end adapted to engage each side of the rail base, and a body portion formed with outwardly and oppositely disposed members intermediate its ends adapted to contact with a cross-tie said body portion having a longitudinal slit therethrough intermediate its ends.

3. A rail anchor formed from a single

piece of metal provided with a jaw clamping member at one end and a gripping member at its other end for engaging each side of the rail base, a body portion slit therethrough intermediate its ends, and outwardly and oppositely disposed members formed intermediate its ends and adapted to engage a cross-tie.

4. A rail anchor formed from a single piece of sheet steel with a clamping member at each end adapted to clamp each side of the rail base, a body portion longitudinally slit therethrough intermediate its ends, and laterally and oppositely disposed extensions formed intermediate its ends adapted to engage a cross-tie.

5. A rail anchor formed from a single piece adapted to engage the rail base, comprising an overlapping jaw member at one end and a clamping member at its other end, a body portion slit longitudinally therethrough between its ends, and longitudinal outwardly and oppositely disposed members formed intermediate its ends adapted to engage a cross-tie.

HARRY G. NORWOOD.
